UNITED STATES PATENT OFFICE.

LUTHER S. HOPKINS, OF DUBUQUE, IOWA.

NONSET AUTOMATIC PHONOGRAPH STOP.

Continuation of application Serial No. 511,032, filed October 28, 1921. This application filed July 21, 1922. Serial No. 576,441.

To all whom it may concern:

Be it known that I, LUTHER S. HOPKINS, a citizen of the United States, and a resident of the city of Dubuque, in the county 5 of Dubuque and State of Iowa, have invented certain new and useful Improvements in a Nonset Automatic Phonograph Stop; and I do hereby declare that the following is a full, clear, and exact description 10 of the same, reference being had to the accompanying drawings and to the numerals of reference marked thereon, which form a part of this specification.

This invention relates to an improved 15 type of automatic non-set phonograph stop wherein a member attached to and movable with the tone arm is adapted, by frictional contact with a mechanism mounted on a slideable bar carrying a brake shoe, to cause 20 engagement of the brake shoe with the turntable when the tone arm ceases to move radially across a record.

This application is a continuation of my 25 pending application for a non-set phonograph stop, filed Oct. 28, 1921, Serial No. 511,032.

It is an object of this invention to provide a phonograph stop adapted to automatically stop the phonograph motor when 30 the playing needle reaches the innermost groove of a phonograph record.

It is also an object of this invention to provide a phonograph stop that is automatically reset by the act of restarting the 35 phonograph.

It is a further object of this invention to provide a phonograph stop mechanism adapted to be actuated by a projection on the phonograph spindle when the tone arm 40 ceases to move toward the center of the record for any reason.

It is an important object of this invention to provide a mechanism adapted to provide either a stop for a phonograph 45 turntable, or the combination of a stop and a switch for an electrically driven phonograph adapted to release upon stoppage of the movement of the tone arm.

It is a further important object of this 50 invention to provide a non-set automatic phonograph stop wherein a member actuated by a turntable spindle and means carried by a tone arm are adapted to coact with control means on a slideable brake 55 shoe bar to cause automatic stopping of the phonograph at a predetermined time.

Other and further important objects of this invention will be apparent from the disclosures in the specification and the accompanying drawings. 60

The invention (in a preferred form) is illustrated in the drawings and hereinafter more fully described.

On the drawings:

Figure 1 is a top plan view of a phonograph showing the record and turntable partly broken away to disclose a stop mechanism embodying the preferred form of this invention as applied to a spring motor phonograph. 65

Figure 2 is an enlarged section on the line 2—2 of Figure 1.

Figure 3 is an enlarged fragmentary view of the release mechanism just prior to operation thereof. 75

Figure 4 is a view similar to Fig. 3 disclosing a locking movement about to cause release of the brake shoe bar.

As shown on the drawings:

The reference numeral 1 indicates a 80 phonograph cabinet provided with a usual motor board 2, turntable shaft or spindle 3, and turntable 4 provided with a depending flange 5 around the periphery thereof. A grooved disc phonograph record 6 is 85 positioned on the turntable by means of the spindle 3. A swinging tone arm 7 is supported in a standard or base 8 and carries a sound box 9 having a stylus 10 thereon. 90

An arm or rod 11 carrying on its outer end a circular segment 12, is rigidly attached to the supported end of the tone arm and projects beneath the turntable 4. The axis of the circular segment 12 corresponds to that of the tone arm 7 and as the tone arm swings over the turntable the segment swings correspondingly beneath the turntable. The ends 13 of the circular segment 12 are bent backwardly to permit engagement of the segment with a spring-actuated member to be described hereinafter. 95

Radially positioned upon the motor board 2 below the turntable 4 is a slideable starting or brake bar 14, the outer end of which projects beyond the flange 5 of the turntable and is bent upwardly to form an integral thumb piece 15. Struck upwardly from the material of the bar is a hook-shaped holder 16 to hold a brake shoe 17, 110 of suitable frictional material, in a position to bear against the flanges of the

turntable when the brake bar 14 is released. The bar 14 is provided with a straight longitudinal guide slot 18 near the brake shoe holder 16 and with an L-shaped slot 19 located near the other end of the bar. Screws 20 project through the slots 18 and 19 and through washers 21 disposed above and below the bar 14. Struck up from the bar 14 between the slots 18 and 19 is a lug 22 to which one end of a coil spring 23 is secured. The other end of the spring 23 is secured to the motor board 2.

The inner end of the bar 14 is bent upwardly at 24 to afford a raised support 25 for an inserted pivot screw 26. Adjacent the bend 24 a stop lug 27 is struck upwardly from the bar 14. Rotatably mounted on the pivot screw 26 is an oscillating bell crank or double armed lever 28, the longer 20 arm 29 of which is positioned to be actuated by two diametrically opposed pins 30 mounted on a star wheel 31 rotatably mounted on the bar 14. Attached to the turntable spindle 3 is a projection or finger 32 adapted to 25 contact the various points of the star wheel 31 to cause rotation thereof when the brake bar 14 is in its inner position. The arm 29 of the bell crank 28 is forked with the ends 33 and 34 of the fork re-entrant so that as 30 the star wheel revolves counterclockwise the pins 30 will act on the inner surface of the form end 33 to throw the bell crank 28 to the left, bringing the end 34 into a position to interfere with one of the pins 30 after a 35 further half revolution. The short arm 35 of the bell crank 28 supports a spring 36 on the outer end of which is mounted a friction member 37 by means of a channel shaped holder 38 having a comparatively stiff ex- 40 tension 39, the end of which rests on the lug 27. The extension 39, in connection with the spring 36, serves to keep the lever arm 29 normally at its extreme right position and to snap it back again after a pin 45 30 engages with the fork 33 to throw the lever to the left.

The operation is as follows:

This non-set automatic phonograph stop is adaptable for use with practically all 50 types of phonographs in place of the ordinary brake for the turntable thereof.

It will be apparent that when the tone arm is swung out to engage the stylus in the outermost groove of the record, the segment 55 carrying arm 11 swings with it, and engages with the friction member 37 only when most of the record has been played, i. e., when the tone arm has swung inwardly for a considerable distance. Normally the brake bar 60 14 is in its outermost position wherein the brake shoe 17 is in contact with the turntable flange 5 holding the turntable and driving motor stationary. To start the phonograph the brake bar 14 is pushed inwardly by the thumb piece 15, which is con-

veniently located in place of the usual manually operating brake, until the curved end of the L slot 19 is reached, when the spring 23 acts to pull the brake bar sideways to permit the screw to seat in the curved end of slot 19 to hold the brake bar in its inner position with the brake shoe 17 out of engagement with the turntable flange 5.

Rotation of the turntable spindle 3 causes the projection 32 thereon to engage with one of the points of the star wheel 31 to cause a partial revolution thereof at each revolution of the spindle, when the brake bar 14 is in its inner position. When, by the rotation of the star wheel, one of the pins 30 engages with the inner surface fork end 33 of the lever 28, said lever is temporarily swung to the left until the pin slips past the end 33 of the fork, when the spring 36 serves to snap the lever 28 back into its normal position. It will be apparent that the star wheel 31 and lever 28 function in a manner somewhat similar to the escapement wheel and lever of a watch or clock.

As the tone arm and stylus travel inwardly over the record being played, the segment 12 on the arm 11 is gradually brought into engagement with the friction member 37 with sufficient pressure to prevent a return of the lever 28 into its normal position after engaging with one of the pins 30 by overcoming the tendency of the spring 36 to pull the friction member 37 over the surface of the segment. However, as long as the tone arm and segment 12 are moving inwardly, the segment carries the friction member along with it and so causes a return of the lever 28 into its normal position.

When the stylus reaches the last or inner groove of the record the tone arm and segment stop moving inwardly thereby holding the friction member stationary until one of the pins 30 snaps the lever 29 to the left when the friction member holds the lever in this position, where the fork end 34 is in a position to catch the pin on its outer surface, as shown in Fig. 4, after a further half revolution of the star wheel, thus locking the star wheel, and causing the spindle projection 32 to throw the slideable brake bar slightly away from the spindle whereby the curved end of the L-slot is moved away from the screw 20 allowing the spring 23, which was tensioned when the brake bar 17 was pushed inwardly, to automatically act to slide the brake bar outwardly into normal braking position with the brake shoe 17 contacting the flange of the turntable, as with an ordinary brake.

It will be evident that the brake is not released by swinging the tone arm outwardly, thus permitting a change of records or shutting down the phonograph without attention from the operator. The stop

mechanism is automatic as it is reset by the act of starting the phonograph and so far as the operator is concerned needs absolutely no attention as all that is evident 5 is the results produced thereby. In an apparatus such as a phonograph, such a simple automatic non-set stop is an immense advantage because very few of the users thereof have any knowledge of the mechanism of the phonograph.

10 I am aware that numerous details of construction may be varied through a wide range without departing from the principles of this invention, and I therefore do 15 not purpose limiting the patent granted otherwise than necessitated by the prior art.

I claim as my invention:

1. A non-set phonograph stop comprising 20 a slidable bar, a control spring connected thereto, a brake shoe on said bar, a rotatable member on said bar, a member mounted on a phonograph spindle for rotating said rotatable member, a bell crank pivoted on said bar adapted to be actuated by said 25 rotatable member, a spring carried by said bell crank, a friction member supported on said spring, an extension on said spring, engaging said bar, and means carried by a phonograph tone arm adapted to friction-

ally engage said friction member and cause 30 release to permit said control spring to slide the bar into a position wherein the brake shoe will stop the phonograph when the tone arm stops moving inwardly across a record.

2. A non-set phonograph stop comprising a spring controlled slidable stopping bar, a rotatable member on said bar, means mounted on the phonograph spindle adapted to rotate said rotatable member, a bell crank 40 adapted to be actuated by said rotatable member, a spring carried by said bell crank, a holder thereon, a friction member in said holder, an extension on said holder frictionally contacting said bar, and means frictionally co-acting with said friction member adapted at a predetermined time to hold said bell crank in a position to interfere with the rotation of said rotatable member thereby causing release of said slidable bar 45 and stopping of the phonograph.

In testimony whereof I have hereunto subscribed my name in the presence of two subscribing witnesses.

LUTHER S. HOPKINS.
